J. C. NOZISKA.
MARKER AND DIVIDER FOR MERCHANDISE.
APPLICATION FILED MAY 9, 1917.

1,317,589.

Patented Sept. 30, 1919.

UNITED STATES PATENT OFFICE.

JOHN C. NOZISKA, OF COLOME, SOUTH DAKOTA.

MARKER AND DIVIDER FOR MERCHANDISE.

1,317,589.

Specification of Letters Patent. Patented Sept. 30, 1919.

Application filed May 9, 1917. Serial No. 167,545.

To all whom it may concern:

Be it known that I, JOHN C. NOZISKA, a citizen of the United States, residing at Colome, in the county of Tripp and State of South Dakota, have invented certain new and useful Improvements in Markers and Dividers for Merchandise; and I do hereby declare the following to be a full, clear, and exact description of the invention, such as will enable others skilled in the art to which it appertains to make and use the same.

This invention relates to markers and dividers and more particularly to markers and dividers especially adapted for use in a general store.

An object of the invention is the provision of means for dividing one class of merchandise from the other and to provide means for designating each class.

Another object of the invention is the provision of means for dividing one customer's grocery order from another to prevent the two orders from becoming confused or mixed.

Another object of the invention is the provision of means for removably attaching the customer's order list directly to the divider, so that the same will not be lost or mislaid.

A further object of the invention is the provision of means for dividing different classes of merchandise positioned on store shelves from each other.

A further object of the invention is the provision of a marker and divider for general store use that will be economical to manufacture, durable in construction and can be sold at a comparatively small sum.

With these and other objects in view, the invention consists in the novel construction, arrangement and formation of parts as will be hereinafter specifically described, claimed and illustrated in the accompanying drawing, in which:

Figure 1 illustrates a perspective view of the improved divider and marker,

Fig. 2 represents a cross sectional view taken on the line 2—2 of Fig. 1,

Fig. 3 represents a perspective view of a slightly modified form of the invention, and

Fig. 4 represents a detail cross sectional view taken on the line 4—4 of Fig. 3.

Referring to the drawing in detail wherein similar reference numerals designate

corresponding parts throughout the several views, the numeral 1 indicates the improved customer's grocery divider as a whole and the same consists of a central vertical plate 2 preferably formed of metal having end supporting feet 4 formed by slitting the metal plate and bending the same at right angles to the plate 2 in one direction, as at 3, and a central supporting foot 5 formed by bending the central section of the slit portion at right angles to the plate 2 in a direction opposite to the end supporting feet 4.

The vertical plate 2 has secured on each side thereof spring clips 6 and 7 each formed of a single piece of wire. The clips 6 and 7 are of approximately U-shaped formation and have the leg portions thereof bent to form spring coils 8 which normally hold the bodies of the clips 6 and 7 in engagement with the vertical plate 2. The terminals 75 of the clips 6 and 7 are looped as at 9 and receive suitable fastening elements 10, which extend through the vertical plate 2 and hold the clips in position.

In use the improved customer's grocery divider is placed on the floor or store counter and the groceries belonging to the different orders are piled up on each side of the divider and the vertical plate 2, supported by the feet 4 and 5, prevents the two orders from getting mixed. The spring clips 6 and 7 support the order lists and prevent the same from getting lost or mislaid, and hold the same so that the clerk or clerks filling the orders can refer to the same at any time.

Figs. 3 and 4 represent a slightly modified form of the divider and marker and the same consists of a central vertical plate 11 having the lower portion thereof bent at right angles to form one side 12 of a supporting base 13. A plate 14, having a right angular portion 15 secured to the central plate 11 by means of suitable fastening elements 16, forms the opposite side of the supporting base 13 and with the portion 12 holds the vertical plate 11 in correct position.

The side 12 of the supporting base 13 is extended beyond the vertical plate 11 as at 16 and has the forward end thereof bent to form a right angular portion 17 to which 105 is secured a card holder 18 constructed of a back plate 19 and inwardly extending flanges 20. As will be noted, the flanges 20

of the holder 18 are disposed horizontally and extend transversely of the supporting device so that, due to the fact that plate 16 extends beyond vertical plate 11, a card or marker may be readily slid into this holder from either end thereof.

The plate 14 forming the opposite side of the supporting base 13 is extended beyond the vertical plate 11 as at 21 and has its forward end bent to form a right angular portion 22 to which is secured a card holder 23 having a base plate 24 and inwardly extending flanges 25.

In use the improved merchandise marker and divider is positioned on the shelf and one class of merchandise is positioned on one side of the vertical plate 11 and another class of merchandise is positioned on the other side. Suitable cards 26 are positioned in the card holders 18 and 23 and designate the class of merchandise positioned on each side of the vertical plate 11. The angular portions 17 and 22 engage the edge of the store shelves and prevent the marker from being pushed to the rear of the shelf and hold the cards in correct position so that they can be easily seen and read.

Copies of this patent may be obtained for five cents each, by addressing the "Commissioner of Patents, Washington, D. C."

What I claim as new is:—

A merchandise marker and divider comprising a vertical dividing plate, outwardly extending flanges formed on the lower longitudinal edge of the plate and extending for equal distances on both sides of the plate to form a supporting base disposed at right angles to the plate, said flanges extending beyond one end of the plate, downturned supporting flanges formed on the forward edge of each flange and extending at right angles thereto, and a card holder secured to the outer face of each of the said vertical supporting elements and provided at its upper and lower edges with retaining flanges extending transversely of the vertical supporting element, said supporting element being spaced away from the dividing plate on each side thereof whereby a marking card may be readily inserted in the free end thereof.

In testimony whereof I affix my signature in presence of two witnesses.

JOHN C. NOZISKA.
